UNITED STATES PATENT OFFICE.

WILLIAM F. D. CRANE, OF EAST ORANGE, NEW JERSEY.

DESIGN FOR A TROLLEY-WIRE CLIP.

SPECIFICATION forming part of Design No. 23,243, dated May 1, 1894.

Application filed March 21, 1894. Serial No. 504,566. Term of patent 14 years.

To all whom it may concern:

Be it known that I, WILLIAM F. D. CRANE, a citizen of the United States, residing at East Orange, Essex county, New Jersey, have invented a certain new and useful Design for a Trolley-Wire Clip, fully described and represented in the following specification and the accompanying drawings, forming a part of the same.

10 The annexed drawings illustrate a wire suspender clip embodying my design, Figure 1 being an elevation of the same upon the front side; Fig. 2 a bottom view of the same; Fig. 3 an end view of the same; Fig. 4 a cross section on line *x*, *x*, in Fig. 1, and Fig. 5 a cross section on line *y*, *y*, in Fig. 1.

The clip is formed with a suspending shank A and a back plate B, from the ends of which hooks C project forward and downwardly, 20 having on their undersides longitudinal channels D. The plate is sloped downwardly and backwardly from a line E above the under side of the hooks C, as shown at B in Fig. 4, and its lower edge is bent forwardly and upwardly into a hook F, forming a longitudinal channel G, the bottom of which is arched

slightly upward in the middle, as indicated by comparison with the straight dotted line H in Fig. 1. The under side of the hook F is tapered upwardly into a thin edge at each 30 end of the channel G, being arched slightly upon the under side, in opposition to the bottom of the channel. The front edge of the hook is, at each end, tapered backwardly to the bottom of the channel G, as shown at H 35 in Fig. 2, and thence upwardly with a thin edge I to the rear side of the channel D in the hooks C, as shown in Figs. 1 and 2.

The above described suspender or clip is used for supporting a trolley wire above the 40 railway track of electric cars.

Having thus set forth the design, what I claim herein is—

The design for a trolley wire clip, herein shown and described.

In testimony whereof I have hereunto set my hand in the presence of two subscribing witnesses.

WILLIAM F. D. CRANE.
